US00D786829S

(12) **United States Design Patent** (10) **Patent No.:** **US D786,829 S**
(45) **Date of Patent:** **** May 16, 2017**

(54) **WIRELESS SPEAKER**

(71) Applicant: **Beijing Xiaoniao Tingting Technology Co., LTD**, Beijing (CN)

(72) Inventors: **Wei Wang**, Beijing (CN); **Jie Zhang**, Beijing (CN); **Lin Wang**, Beijing (CN)

(73) Assignee: **Beijing Xiaoniao Tingting Technology Co., LTD**, Beijing (CN)

(**) Term: **15 Years**

(21) Appl. No.: **29/549,591**

(22) Filed: **Dec. 27, 2015**

(30) **Foreign Application Priority Data**

Jun. 30, 2015 (CN) 2015 3 0234806
Jun. 30, 2015 (CN) 2015 3 0234808
